UNITED STATES PATENT OFFICE

GASTON BOISSONNAULT, OF VALLEY STREAM, NEW YORK, ASSIGNOR TO CHARLES P. KIMMEY, TRUSTEE, OF NEW YORK, N. Y.

LOCK PROTECTION

Application filed November 17, 1925. Serial No. 69,573.

The objects of this invention are to provide simple and effective means for protecting door locks and the like which will be readily attachable to existing door locks and which will be fully effective to give notice of any 5 tampering with or injury to the lock.

A further special object is to provide an effective alarm which can be rendered inoperative so that an alarm will not be given 10 necessarily when the lock is operated by one having a right to do so.

Another object of the invention is to provide the alarm in the form of an attachment applicable as a single unit over standard locks 15 now in service.

Other objects and the various novel features of the invention by which such objects are attained will all appear in the course of the following specification.

20 The drawings accompanying and forming part of this specification illustrate the invention embodied in a number of different practical forms, but it is to be understood that the structure may be further varied without 25 departure from the spirit and scope of the invention as hereinafter defined and broadly claimed.

Figure 1 is a front view of the combined protector and alarm as applied to a standard 30 "Yale" lock.

Figure 2 is a vertical sectional view of the same showing the cover of the device unlocked to gain access to the keyway of the protected lock.

35 Figure 3 is a rear view of the device.

Figures 4 and 5 are diagrammatic views of a closed circuit and open circuit system respectively which may be used with the device.

40 The protector which is applied to the front of the door 10 comprises in the present disclosure, a small casing 11 having a chamber 12 in its upper portion containing the electrical mechanism and a lower chamber 13 enclosing the face 14 of the lock 14a. The lock enclosing chamber is closed by a cover 15 hinged at its lower end at 16 so that it will automatically drop down when released and 45 this cover carries at its upper end, a cupped

projection 17 to engage over and make contact with an insulated circuit terminal 18.

The upper chamber 12 of the protector casing is closed by a door 19 hinged at the side at 20 and secured by a lock 21. This 55 door engages over the contact making projection 17 of the lower cover 15, as shown in Figure 1 so as to secure the lock cover 15 in its locked protective position.

The upper portion of the casing is separated by the intermediate partition 22 into the forward compartment 12 and a back compartment 23, the latter housing the wiring connections.

On the back of the partition 22, a base 24 60 of wood or other suitable insulating material is secured, carrying a series of switch points 25 with which the lever 26 cooperates, the spindle 27 of said lever projecting through to the front chamber and there provided with 65 a dial or other suitable indicator 28.

This dial has a finger-hold 29 by which it can be turned and is shown as detachably held on a squared or angular portion 30 of the spindle by the screw 31. Access is had to this 75 screw after removal of a detachable cover plug 32, such construction permitting the position of the dial with respect to the switch arm being readily changed.

The protector is shown secured to the front 80 of the door by screws 33 housed within the casing and which can be reached only when the casing is open.

The removal of the protector casing is made an element of the lock protection by 85 providing in the present disclosure, a spring contact 34 which by engagement with the face of the door is forced into contact with a spring 35 and another door engaging contact 36 cooperating with a contact spring 37. 90 These two pairs of contacts are mounted on the back of the insulating base, the first pair at the top and the second pair at the lower portion of the casing so as to give an alarm if an attempt is made to pry off the protector 95 at the top or at the bottom. The pin contact 18 is shown as of the yielding spring pressed type mounted in an insulating holder 38.

The protector may operate on either the normally closed or the normally open circuit 100

principle. Examples of such circuits will be described before considering the lock guarding mechanism which is applied over the lock on the back of the door.

- 5 In the closed circuit arrangement shown in Figure 4, the closing of the door, by means of a plate 39 completes a circuit between contacts 40, 41. The first of these contacts is connected by conductor 42 with contact 10 spring 35 and from the outer door engaging contact 34, the conductor 43 is shown extending to the inner contact spring 37. The companion or lower door engaging spring 36 is connected by conductor 44 with the pin contact 18. The lock cover 15 is in metallic connection with the casing, which latter may be considered as a common ground, being made a part of the circuit by means of a terminal 45 in electrical connection with the casing. 15 A conductor 46 is led from this terminal to one side of a closed circuit relay 47, the opposite side of which is connected by conductor 48 with a battery or other source of current 49. From the other side of this battery, a conductor 50 leads to the other door terminal 41.

Upon interruption of the circuit described, either by forcing the door, where the circuit would be broken at the points 40, 41, or by forcing the protector casing away from the 20 door, where the circuit would be broken at contact springs 34—35 or 36—37, or by breaking open the casing, whereupon the lock cover 15 would drop down and break circuit with pin contact 18, the circuit through the relay 25 will be interrupted and the relay would then act in the well known manner to close the circuit through the bell or alarm 51 by means of an independent ringing circuit 52. Hence any tampering with the door or with the 30 protector will set off the relay to produce a constant ringing of the alarm. The effect will be the same if the wiring leading to the relay is broken at any point.

Authorized opening of the lock is permitted 45 without setting off the alarm by one having a key to the protector and knowing the necessary combination. Such a party may open the door to the protector by means of a key fitting the protector lock 21, Figure 50 1, holding the lock cover 15 closed while opening the protector door and then turning the dial to carry the switch arm 26 into engagement with the single live contact 25a which is connected by wiring 53 with the battery 55 line 50. The turning of the dial switch to this point, as will be clear from Figure 4, closes a circuit through the relay entirely independently of the protective circuit, holding the alarm inactive while such person is inserting the key in the door lock and opening the door. Hence the proprietor of a store to which the system is applied, knowing the necessary combination and being familiar 60 with the action of the protector, may open his store without unnecessarily setting off the 65

alarm. A secretly placed switch may then be operated to render the system inoperative while the door remains open.

In an open circuit system such as indicated in Figure 5, all the switch points are energized with the exception of one, denoted 25b, so that to open the circuit and render the system inoperative, a person must know the figure to which the dial must be turned to prevent the giving of an alarm when an 70 authorized entry is made, using the key to the door. The cooperating contacts in this case operate reversely of the above described, that is, when the door is forced, the contact 75 39' closes a circuit with contacts 40', 41'; or when the protector casing is forced, contact springs 34', 35' or 36', 37' close a circuit, or when the lock cover 15 is forced, the pin contact 18' closes the circuit energizing the 80 relay 47', causing that to set into constant 85 operation, the alarm 51'.

What is claimed is:

1. In lock protection, the combination with a key actuated lock, of a movable cover over 90 said lock and which can be opened to expose the lock for insertion of the lock actuating key, signal means operable by such opening of the lock cover, control mechanism for rendering said signal means inoperative and a movable cover over said control mechanism for holding the lock cover closed over the lock and whereby upon release of said second cover the control mechanism 95 will be exposed to enable one familiar with the same to render the signal means inoperative when the lock cover is thus released by said second cover. 100

2. In lock protection, the combination with a key actuated lock, of a movable cover over 105 said lock and which can be opened to expose the lock for insertion of the lock actuating key, signal means operable by such opening of the lock cover, control mechanism for rendering said signal means inoperative and a movable cover over said control mechanism for holding the lock cover closed over the lock and whereby upon release of said second cover the control mechanism will be exposed to enable one familiar with the same 110 to render the signal means inoperative when the lock cover is thus released by said second cover, said control mechanism including a combination dial concealed by the second door when closed and exposed upon the 115 opening of said second door. 120

3. In lock protection, a casing for housing the key-way of a lock, said casing including a hinged cover shiftable to conceal or to expose the key-way and a door overlying 125 said cover, signal means operable by the opening of said cover and control mechanism for rendering said signal means inoperative independently of the action of said cover, said control mechanism being housed within the 130 casing behind said door. 135

4. In lock protection, a casing for covering a lock, said casing having a key controlled door and a lock protecting cover positioned to be held by the door in its lock protecting position, a dial in the casing exposed by the opening of said key controlled door, an alarm operable by the opening of the cover and means operable by said dial for preventing operation of the alarm by the cover 10 when the dial is placed in a predetermined position.

5. In combination with a key actuated door lock, a movable cover for said door lock and means for mounting the same in position to expose or to prevent access to the key-way of the lock, alarm mechanism retained inoperative by said cover when the cover is closed and operable on the opening of the cover, selective switch mechanism for rendering the alarm mechanism inoperative when the cover is open, a door providing access to said switch mechanism and overlying the cover in its closed relation, a lock for said door and means for holding the cover closed when the door is first opened to give access to the switch mechanism.

In witness whereof, I have hereunto set my hand this 1st day of October, 1925.

GASTON BOISSONNAULT.
